UNITED STATES PATENT OFFICE.

WILLIAM BUTTLER, OF REDKEY, INDIANA.

DESIGN FOR A LAMP-CHIMNEY.

SPECIFICATION forming part of Design No. 24,472, dated July 16, 1895.

Application filed May 21, 1895. Serial No. 550,141. Term of patent 14 years.

To all whom it may concern:

Be it known that I, WILLIAM BUTTLER, of Redkey, in the county of Jay and State of Indiana, have invented a new and original Design for Lamp-Chimneys and Similar Articles, of which the following is a full, clear, and exact description, reference being had to the accompanying drawings, forming part of this specification, in which—

10 Figure 1 is a side elevation of a lamp-chimney embodying my new design, and Fig. 2 is a partial top plan view of the same.

15 My design consists in a lamp chimney or shade having at its upper end a circular series of scallops, the intermediate edge portions between the scallops being grooved.

In the drawings, 2 represents the chimney,

having at its upper end a series of scallops 3. The angular portions 4 are grooved on both their inner and outer faces. The number of 20 these grooves is immaterial, one or more giving the characteristic appearance peculiar to my design.

I claim—

The design for lamp chimneys and similar 25 articles substantially as herein shown and described.

In testimony whereof I have hereunto set my hand.

WILLIAM BUTTLER.
